US00D545707S

(12) **United States Design Patent** (10) Patent No.: **US D545,707 S**
Barmettler et al. (45) Date of Patent: **** Jul. 3, 2007**

(54) **PRESSURE GAGE WITH RADIAL CONNECTOR**

(75) Inventors: **Peter Barmettler**, Hunenberg (CH);
Andreas Arnold, Hitzkirch (CH); **Kurt Grunder**, Burg (CH)

(73) Assignee: **WIKA Alexander Wiegand GmbH & Co. KG**, Main (DE)

(**) Term: **14 Years**

(21) Appl. No.: **29/233,500**

(22) Filed: **Jul. 1, 2005**

(51) LOC (8) Cl. **10-04**

(52) U.S. Cl. **D10/85**

(58) Field of Classification Search .... **D10/85; 73/715-722, 431, 732-733; 200/83, 83 B; 200/83 C, 83 L; 324/110-116, 119**
See application file for complete search history.

(57) **CLAIM**

The ornamental design for a pressure gage with radial connector, as shown.

DESCRIPTION

FIG. 1 is a perspective view showing the front of our new design;

FIG. 2 is a perspective view showing the rear of our new design;

FIG. 3 is a right side elevation view of our new design, the left side being a mirror image thereof;

FIG. 4 is a top plan view of our new design; and,

FIG. 5 is a bottom plan view thereof.
